UNITED STATES PATENT OFFICE.

HENRY F. A. KLEINSCHMIDT, OF JOHNSTOWN, PENNSYLVANIA.

SURFACE-GRINDER.

1,225,040.

Specification of Letters Patent.

Patented May 8. 1917.

Application filed October 30, 1916. Serial No. 128,546.

To all whom it may concern:

Be it known that I, HENRY F. A. KLEINSCHMIDT, a citizen of the United States, and resident of Johnstown, in the county of Cambria and State of Pennsylvania, have invented certain new and useful Improvements in Surface-Grinders, of which the following is a specification.

My invention relates to certain new and useful improvements in surface grinding machines with especial reference to grinding machines for use in connection with track work.

Such machines are used for the purpose of restoring to a true running surface the head, or top surface, of rails, where such rails have been worn so as to produce a low spot, or in connection with the welding of rail joints in cases where the head of the rail has become distorted by reason of such welding; also for restoring the running surface at any point in the track where the same may be out of true due to wear or other causes.

In nearly all surface grinding machines heretofore developed for this purpose that portion of the machine which carries the grinding wheel is made to run or slide on the head of the rail itself, thereby reproducing to a certain extent the irregularities existing in the rail; also in some of these machines the forward and back motion of the grinding wheel is accomplished by hand power. My invention does away with all these objections, as the grinding wheel is carried on rigid slides independent of the rail or surface to be ground, and a true surface can be obtained without regard to the condition in which the rail or surface to be ground may be. I also provide for an automatic power driven mechanism for moving the grinding wheel back and forth over the work.

The machine consists essentially of a carriage supporting a motor and grinding wheel shaft, the motor being belted to the grinding wheel shaft directly by means of a leather or chain belt, the latter being preferable. This carriage is supported on a rigid rectangular frame on which the carriage moves to and fro, the rectangular frame being supported at each end on rollers which come in contact with the head of the rail. These rollers remain practically stationary

when the machine is in operation, and their purpose is simply to establish a fixed distance between the carriage and the surface of the rail at any point in the travel of the carriage. Means are also provided for tipping the frame to one side or the other, so that the grinding wheel can be made to grind to the exact contour of the rail head. By means of a round post attached to the end of a car or other support and a sliding attachment to said post, the frame of the machine can be held upright in any position desired.

The invention will be more readily understood by reference to the accompanying drawings, wherein—

Figure 1 is a side elevation of the entire machine;

Fig. 2 is an elevation of the left-hand end of the machine shown in Fig. 1;

Fig. 3 is a plan view of the machine;

Fig. 4 is a sectional view on the lines 4—4 of Figs. 1 and 5;

Fig. 5 is a sectional view on the line 5—5 of Fig. 1;

Fig. 6 is a section on the line 6—6 of Fig. 1;

Fig. 7 is a sectional view on the line 7—7 of Fig. 6;

Fig. 8 is a sectional view on the line 8—8 of Fig. 7;

Fig. 9 is a sectional view on the line 9—9 of Fig. 1;

Fig. 10 is an elevation of a catch employed for holding the reversing lever in position, and

Fig. 11 is a face view of one of the bevel gears of the reciprocating mechanism, a portion of which is best shown in Fig. 4.

Referring to the drawings, and more particularly to Figs. 1 and 3, it will be seen that the grinding device is primarily supported upon wheels or rollers 20 and secondarily supported by the end of a car, a portion of which is indicated at 21. The wheels 20 are intended to rest upon the track rails and serve to support the frame 22 of the machine. The wheels 20 are rotatably mounted on axles or shafts 23, which, as is clearly shown in Fig. 9, have eccentric end portions 25 mounted in the bearings 25', (see Figs. 1 and 9); this expedient being adopted in order to adjust the height of the frame and the parts sup-

ported thereby with relation to the rail. The eccentrically mounted shafts or axles 23 are rotated to accomplish this result by means of levers 24, the lower ends of which are keyed to the eccentric end portions 25 of the axles or shafts 23. The means for operating the arms 24 as required will be described hereinafter.

19 Mounted in the channels of the frame members 22, as best shown in Fig. 5, are castings 26 which provide ways for the guidance of the carriage 27. This carriage serves to support the grinding wheel, the cradle, the motor and related parts, all of which are bodily reciprocated in the frame. 15 The upper portion 28 of the carriage 27 serves to support a swivel nut 29, which co-operates with a worm or screw 30 and a hand wheel 31 for a purpose hereinafter described.

20 Mounted on the trunnions 32 is the cradle, the lower portion 33 of which carries the grinding wheel 34 and the upper portion 35 of which carries the motor 36. A shaft 37 has a bearing in one of the hollow trunnions 32 in the carriage 27, and at the outer end of the shaft 37 is mounted a pulley 38, a hand operated clutch 39 being provided for connecting and disconnecting the pulley from the shaft as desired. This clutch may be of any of the various well known types. A belt extends from one end of the armature shaft to the pulley 38, such belt being indicated in dotted lines in Fig. 1 and numbered 39'.

35 The cradle is mounted in the carriage for limited oscillation on its trunnions 32, the cradle being held in adjusted position by means of the worm 30, which is connected to the upper portion 40 of the frame. The 40 adjustment of the grinding wheel 34 with relation to the rail is secured by manipulating the hand wheel 31. A belt 41 connects the opposite end of the armature shaft to the grinding wheel 34.

45 As a means for causing the reciprocation of the carriage and consequently of the grinding wheel, I provide the worm or screw 42, best shown in Figs. 3 and 5, the same being held against bodily longitudinal 50 movement as well as against rotation, except when operated by the crank 43. In normal operation this crank is held in a fixed position by means of a pin 44 in the handle of the crank 43, which engages with 55 an opening in the frame member. However, at times manual operation of the screw 42 may be desirable and provision is made therefor. The mechanism which co-operates with the screw 42 to cause reciprocation of the carriage includes a pinion 45, fixed to the shaft 31, as best shown in Figs. 4 and 5, this pinion engaging two bevel gears 46, 47, having the same axis of rotation and located on opposite sides of the 60 pinion. The result is that these gears ro-

65 tate in opposite directions. Integral with such gears are sleeves 48, 49, which are mounted in suitable bearings and accommodate tubular envelopes 50 which surround the screw 42. Mounted in a recess which surrounds the envelopes 50 are springs 51, 52, the outer ends of which bear against a nut 53. The exterior of this nut 53 is hexagonal, as best shown in Fig. 5, and is fitted within and slidable upon a yoke collar 54 having teeth or projections 55, 56, upon opposite faces thereof. These teeth or projections are intended to engage with similar teeth 57, 58, upon the gears 46, 47. The collar 54 is caused to alternately engage with the gears 46, 47, by means of the yoke 59, the yoke being fixed to the tube 60, which slides on the rod 84', as best shown in Fig. 4. As a means for holding the tube 60 and likewise the yoke 59 and collar 54 in adjusted positions, I provide the device shown in Fig. 10, which comprises a two-part clamp 61, which has fixed thereto a triangular projection 62 adapted to contact a spring-pressed stud 63 having a triangular end portion and held in proper relation by engagement with a bracket 64, projecting from the casing 65' which surrounds the reversing gear heretofore described. This bracket is best shown in Fig. 5. A rod 84', best shown in Figs. 3 and 4, extends from end to end of the frame 22, being rigidly attached thereto at its ends. On the rod 84', which extends through and beyond each end of the tube 60, are adjustable stops or clamps 64 and 65, as shown in Fig. 3. From the clamps 64, 65, project arms 66, 67, which terminate in stops 68 and 69. (see Fig. 1). The movement of the clamps 71, 70, is limited by the rods 98, 99, passing through the projecting arms 69, 68, so that the stops 65 and 64 cannot be moved except in a certain relation to the stops 71, 70. The outer ends of the rods 72, 73, engage the upper ends of the levers 24 heretofore referred to. The inner ends of the rods are guided in sockets 74, 75, carried by suitable brackets on the carriage. The rods 72, 73, slide freely within said sockets until the ends of the socket members contact with clamps which hold the arms 70, 71, whereupon the rods 72, 73, arms 70, 71, are bodily moved in the direction of movement of the carriage. This continues until the tube 60 contacts with one of the stops 64, 65, when the yoke collar 54 is shifted to change the direction of movement of the carriage 27. Before the carriage has been reversed, however, one of the arms 24 has been shifted, with the result that the corresponding end of the frame has been bodily raised, due to the eccentricity of the axle 23. As the carriage is reversed, the arm 24 is caused to return by the springs 74', the extent of 130

return movement being limited by the stop members 75', which are adjustable by means of the fastening bolt 76. By this means the depth of the cut may be regulated. The length of the cut is controlled by the position of the stops 64, 65, and as these are adjustable the movement of the grinding wheel may be as long or as short as desired. It will be noted that by the arrangement illustrated in Fig. 1 the wheel travels in a plane, except at the end of the stroke when it is lifted and again returned in the same path. This occurs at both ends of the stroke or movement. The extent of lifting movement of the grinding wheel 15 may likewise be controlled by positioning the stops 70, 71, with relation to the stops 64, 65; that is to say, the carriage may be reversed with practically no lifting movement of the carriage at the end of the 20 stroke.

As a means for securing the lateral adjustment of the frame and associated parts, I provide the mechanism best shown in Figs. 1, 7 and 8. As shown in these figures, a bracket 77 is fixed to the end 21 of the car, this bracket carrying a threaded shaft 78. A casting 79 has a recess which accommodates the bracket 77, the parts being held in proper relation by the overhanging bars 80. A nut 81 engages the threaded shaft or worm 78 and is carried by the casting 79. By reason of such construction a rotation of the threaded shaft or worm 78 will cause a bodily lateral movement of the casting 79 and the parts connected thereto. Mounted in sockets 82, 83, carried by the casting 79 is a spindle or hollow standard 84, within which is located a threaded shaft 85, the lower end of which is pinned at 86 to a casting 87, as best shown in Fig. 7. A hand wheel 88 engages the threaded shaft at the upper end, the hub of the wheel finding a bearing on a thinable 89, which bears upon the top of the hollow standard 84. Bodily vertical adjustment of the frame is secured by rotation of the hand wheel, the frame 22 of the machine being connected slidably to said standard by means of the brackets or straps 90, 91, as best shown in Fig. 7.

As a means for securing oscillation of the grinder frame in order to grind at different angles other than actual horizontal position, I provide the mechanism best shown in Figs. 6 and 7. The frame members 22, as best shown in Fig. 6, carry a transverse shaft 92, on which a casting or a vertical frame member 93 is mounted. The lower end of this casting or frame member 93 is provided with a lateral projection 94, which engages a hook 95, held by a bolt 96 to the casting 87. The projection 94 is arcuate, as best shown in Fig. 6, which permits of the shifting of the frame member 93 with relation

to the casting 87 and consequently the shifting of the entire frame 22 and associated parts with relation to the car 21. The shifting action is secured by means of the worm 97, carried by brackets mounted on the strap 91, as best shown in Fig. 7, the worm 97 engaging an arcuate rack 98 fixed to the upper end of the vertical frame member 93. In this frame member I provide an arcuate slot 99 and a bolt 100 passes through this slot which serves to hold the parts in adjusted position after having been located by the aid of the worm 97. It will be seen that while the car 21 serves to support one end of the grinder frame under certain circumstances, there is nothing to prevent the elevation of the grinder frame with relation to the end 21 of the car under the action of the eccentric shaft 23 at that end of the frame. This is true because the straps 90, 91, will slide freely on the hollow standard 84, and the rod 85 will rise in the standard carrying the hand wheel 88 therewith.

It is thought the operation of the device has been fully explained in connection with the description of the mechanism. It might be stated, however, that after having located the apparatus in proper position the grinding wheel 34 is lowered relative to the carriage and track rail to be operated upon, by rotating the same about the trunnions 32 as a pivot through the medium of the hand wheel 31 and worm 30. The electric motor is then started which causes the rotation of the grinding wheel and starts reciprocation of the carriage which carries the grinding wheel and motor. The length of stroke of the carriage is determined by the adjustment of the stops 64, 65. It may be desired to discontinue the automatic reciprocation of the carriage and parts, in which case the clutch 39 is disengaged from the shaft 37, this allowing the pulley to run idly. In such case the carriage may be shifted manually by means of the hand lever 43 when found desirable or necessary.

One of the advantages in the present construction is that the carriage is reciprocated by the use of a clutch which is positive and still without shock to any of the parts.

This result is secured by reason of the nut 53 and the springs 51, 52, which bear against the end of the nut. (See Fig. 4). The carriage is reciprocated through the springs. After the clutch collar 54 is disengaged from one gear and brought into engagement with the opposite gear the nut 53 must be given several turns before sufficient compression is exerted on the spring to cause the shifting of the carriage. Thus the only shock of reversal is that of stopping the rotation of the nut and clutch collar and this is very slight.

Obviously the construction is capable of much modification and such modifications

as are within the scope of my claims I consider within the spirit of my invention.

I claim:

5. In a grinding machine, the combination of a frame, means for supporting the same above a rail, a carriage reciprocably mounted on said frame, a grinder frame mounted for oscillation on said carriage, a grinding wheel and means for rotating said wheel and for causing the reciprocation of said carriage, substantially as described. 70
10. 2. In a grinding machine, the combination of a frame, means for supporting the same above a rail, a carriage reciprocably mounted on said frame, a grinding wheel and motor mounted on said carriage, means for causing the reciprocation of said carriage and means adapted to be actuated near the end of the stroke of said carriage 75 for causing a bodily lifting of said frame. 15
15. 3. In a grinding machine, the combination of a frame, means for supporting the same above a rail, a carriage reciprocably mounted on said frame, a grinding wheel and motor mounted on said carriage, means for causing the reciprocation of said carriage and means adapted to be actuated at the limit of the reciprocations of said carriage for causing an alternate raising and 80 lowering of the ends of said frame and associated parts, substantially as described. 20
20. 4. In a grinding machine, the combination of a frame, means for supporting the same above a rail, a carriage reciprocably mounted on said frame, a grinder frame mounted for oscillation on said carriage, a grinding wheel and a motor mounted on said grinder frame, automatic means for causing the reciprocation of said carriage 85 and manually operable means for causing oscillation of said grinder frame, substantially as described. 25
25. 5. In a device of the class described, the combination of a frame, means for supporting the same above a track rail, an eccentric shaft disposed between said track rail and said frame, a lever for causing rotation of said eccentric shaft and consequently a change in the distance between said frame 90 and said rail, a carriage reciprocably mounted upon said frame and means actuatable by said carriage near the end of the stroke thereof for actuating said lever to cause the elevation of said frame, substantially as described. 30
30. 6. In a device of the class described, the combination of a frame, means for supporting the same above a track rail, means for causing limited variation in the distance 95 between said frame and said track rail, a lever for actuating said adjusting means, a carriage reciprocably mounted upon said frame, a grinding wheel mounted upon said carriage, means for causing automatic reciprocation of said carriage and means mov- 100
10. able by said carriage for actuating said lever, thereby causing a bodily elevation of said frame and consequently said grinding wheel at the end of the stroke of said carriage, substantially as described. 105
15. 7. In a device of the class described, the combination of a frame, a carriage reciprocably mounted upon said frame, a grinding wheel carried by said carriage, automatic means for causing the reciprocation of said carriage, said means including a fixed screw and a rotatable nut carried by said carriage, and a spring interposed between said nut and said carriage whereby the force exerted to cause the movement of said carriage 110 is exerted through said spring, substantially as described. 115
20. 8. In a device of the class described, the combination of a frame, a carriage reciprocably mounted upon said frame, a grinding wheel mounted upon said carriage, a motor also mounted upon said carriage, means for causing the reciprocation of said carriage, said means including a fixed worm and a rotatable nut movable with said carriage and 115 a spring disposed at each end of said nut and so arranged that the force tending to cause a movement of said carriage is exerted through one of said springs, substantially as described. 120
25. 9. In a device of the class described, the combination of a frame, a grinding wheel, a motor reciprocably mounted with relation to said frame, and means for causing the reciprocation of said grinding wheel, said means including a bevel pinion, two bevel gears engaging opposite sides of said pinion, said bevel gears having toothed faces, a clutch member having teeth adapted to engage the toothed faces of said gears, a 125 nut upon which said clutch member slides and a fixed screw with which said nut engages, springs interposed between the ends of said nut and the portions of the parts to be reciprocated and means for causing the shifting of said clutch member into engagement with alternate gears, the arrangement being such that a positive clutch is employed while the shock of reversal is cushioned by said springs, substantially as described. 130
30. 10. In a device of the class described, the combination of a frame, means for supporting the same above a track rail, an end support by means of which said device is maintained in proper vertical position, a motor 135 and grinding wheel carried by said frame, and means for moving said frame laterally with respect to said end support, substantially as described. 140
35. 11. In a device of the class described, the combination of a frame, means for supporting the same above a track rail, an end support by means of which said device is maintained in proper vertical position, a motor and grinding wheel carried by said frame 145

and means for lifting said frame vertically with relation to said end support, substantially as described.

12. In a device of the class described, the combination of a frame, means for supporting the same above a track rail, an end support by means of which said device is maintained in proper vertical position, a motor and grinding wheel carried by said frame and means for rocking said frame about a center in the plane of the top surface of said track rail, substantially as described.

13. In a device of the class described, the combination of a frame, means for supporting the same above a track rail, an end support by means of which said device is maintained in proper vertical position, a motor and grinding wheel carried by said frame and means associated with said end support 20 and said frame for adjusting the same laterally, lifting the same vertically or rocking the same about a center in the plane of the top surface of said track rail, substantially as described.

25 14. In a grinding machine, the combination of a frame, a carriage reciprocably mounted on said frame, a grinding wheel

mounted on said carriage, automatic means for causing the reciprocation of said carriage, adjustable means for controlling the extent of reciprocation of said carriage, automatic means for lifting said grinding wheel at the end of the stroke of said carriage, and manually operable means for raising said grinding wheel a substantial distance above said track, substantially as described.

15. In a grinding machine the combination of a frame, a carriage reciprocably mounted on said frame, a grinding wheel 40 mounted on said carriage, means for causing the reciprocation of said carriage, means for controlling the extent of reciprocation of said carriage, means for lifting said grinding wheel at the end of the stroke of said carriage, and means for raising said grinding wheel a substantial distance above said track, substantially as described.

Signed at Johnstown, Pa., this 27th day of October, 1916.

HENRY F. A. KLEINSCHMIDT.
